UNITED STATES PATENT OFFICE.

FRANK ZALESKI, OF BOSTON, MASSACHUSETTS, ASSIGNOR TO REECE SHOE MANUFACTORY COMPANY, OF BOSTON, MASSACHUSETTS, A CORPORATION OF MAINE.

SEWING MACHINE.

Application filed August 7, 1922. Serial No. 580,276.

This invention is a novel sewing machine, more especially a shoe sewing machine of the class known as a welt-and-turn machine, in which the shoe insole is stitched to the shoe upper and, preferably, also to the welt strip. The principal object of the present invention is to improve the operation of such a machine and more especially to improve the work supporting and engaging devices and their operation, the welt feeding and applying means and their operation, and the mode of actuation of the looper which cooperates with the needle during stitching. Other objects and advantages of the present machine will be explained hereinafter or will be apparent to those skilled in the art. To the attainment of such objects and advantages the present invention consists in the novel machine, mechanisms, combinations, arrangements and devices shown, described and claimed.

In the accompanying drawings forming a part hereof, Figure 1 is a left elevation of the pertinent parts of a shoe stitching machine embodying the present invention.

Figure 2 is a right elevation showing certain of the same parts.

Figure 3 is a left elevation on an enlarged scale of certain details shown in Figure 1. In Figures 1, 2 and 3 the parts are shown in the position they assume in the final stop position of the machine, with the needle fully retracted from the work.

Figure 4 is a view corresponding with Figure 3, but with the parts shown in a different stage of operation, while the needle is still engaged in the work, but has begun its retracting movement.

Figure 5 is a plan view of certain parts, partly in section on the line 5—5 of Figure 3.

Figure 6 is a diagram showing the relation of the shoe, the channel guide, the welt strip and the welt guide, which latter is also termed a work gage, as the work bears against it at certain times.

Prior welt and turn stitching machines as shown in prior patents of Zaleski, et al., No. 1,288,366 of December 17, 1918 and No. 1,361,952 of December 14, 1920, which may be referred to for general features and matters of construction and operation which do not form a part of the present invention or are not illustrated herein.

As in said prior machines, the present in-

vention may comprise the usual stitching instruments, in this case including the work rest or bumper A against which the workman holds the shoe during stitching, the channel guide B which engages with the pre-formed channel in the sole, the oscillating, curved, hooked needle C, the looper D which places the thread in the barb of the needle, the thread hook or finger E, cooperate with the looper, the feed device or awl G, and the instrument H known as the back gage, against which the work contacts at certain times, and which also serves as a guide and feeder for the strip or welt in stitching welt shoes. The present invention relates more especially to the back gage H which is mounted at the forward end of its sliding shank h, and the work rest A upon a similar shank a, and the looper and its actuation. It will be understood that the machine is provided with the usual take-up which, however, is not indicated in the drawings hereof, although actuated from the same operating shaft.

In Figures 1 and 6 the shoe X is indicated, with the lip x of the insole, and the edge of the upper y as well as the welt or strip w, which parts are to be stitched together progressively around the shoe in the usual manner.

Most of the parts herein shown are mounted on a frame part or upright wall 10. This is the left hand one of the two spaced apart walls shown in the prior machines. The parts to the left of the wall, namely, the parts seen in Figs. 1, 3, 4 and 5 may be termed outside parts for convenience, and similarly those to the right of the wall or between the walls, shown in Fig. 2, may be called inside parts. The main or operating shaft 11 utilizes the frame wall 10 as one of its bearings. This may be provided with cranks rather than cams for operating the greater part of the stitching instruments, as in said prior machines. Thus, an outside or left hand crank 12 is shown which actuates the outside connections, while an inside or right hand crank 13 is indicated in Fig. 2 for actuating the connections there shown, and others. The usual hand wheel may be provided at one end of the operating shaft and any suitable stop motion for stopping the machine with the needle retracted, for example such a stop motion as indicated in

Patent No. 1,420,580 of June 20, 1922, in which the final retraction of the needle is without loop, so that the work may be readily removed.

5 The crank driven connections for operating the sewing instruments may be of various forms. For example, the needle C may be actuated from the inside crank 13. The crank carries a pitman 15, the movements of which are controlled by a swinging arm 16 pivoted forward of the main shaft. The extremity of the pitman is connected by a link 17 to the big lever 18 fulcrumed at its rear end upon an axle 30 and at its front end connected by a curved link 19 with the pivoted needle block which carries the needle C. Thus the needle is caused to oscillate, and when moving forwardly it passes through the welt and upper and insole lip and then 10 receives thread from the looper D afterwards retracting with the loop and thus forming chain stitches in the usual manner.

The outside crank 12 carries a pitman 21 which is controlled in its movements by a 15 swinging arm 22 pivoted at 23 on a fixed bracket 24. Incidentally, I prefer to utilize the swing of the lever 22, which operates through a toothed connection and a swinging arm 25, for actuating pin c' on the usual needle guide, which is the member sliding on the curved needle for giving it support against breakage.

The crank 12 and pitman 21 are utilized to actuate several elements of the machine. 20 A link 26 is shown extending from the extremity of the pitman 21 to an arm 27. This is the forward arm of a three-armed lever having an upward arm 28 and a downward arm 29, all rocking together about the fulcrum or axle 30 near the rear of the machine. The looper D may be actuated from the upward arm 28 through a long connecting rod 31 extending forwardly to the upward arm of a bell crank lever 32, the forward arm of which is provided with a toothed sector 33 25 engaging a pinion 34, shown in Fig. 1, which is directly connected to a bevel gear 35, shown in Fig. 2, which drives a bevel gear 36 mounted at the upper end of the rotating looper D, thus giving the eccentric extremity of the looper a circular motion around the path of the needle, for laying the thread in the barb thereof.

The work rest A has its shank a fitted and guided at the inside of the frame wall, as shown in Fig. 2. A confining plate 39 guides its front end and a plate or block 40 serves the same function at the rear. A spring 41 constantly pulls forward on the work rest, permitting it to yield backwardly at certain times, for example, during the feeding of the work to adapt itself to the position of the work. The work rest is to be locked forward at certain points in the cycle of operations namely, during the re-

traction of the needle, and for this locking the following mechanism may be employed. The locking devices are controlled by a lever 42 pivoted at its middle part, its upper end being pulled forwardly by a spring 43, seen 70 in Fig. 1. The movements of the lever 42 are controlled by a cam 44 which is associated with and rocks in time with the three-armed lever 27-29. The cam acts against a roll 45 at the upper end of the lever to 75 throw it rearwardly at certain times, thus throwing forwardly the lower end of the lever, where it carries a roll 46 arranged to press forwardly against a sliding pin 47. The pin 47 is for unlocking the clutch device, which consists of the roller or ball 48 mounted between the shank a of the work rest and a fixed wedge surface 50 above the same. The elements 47-50 are confined between the block 40 and the wall 10. A spring 80 pressed rod 49 tends always to press the roller into wedging engagement with members a and 50. The pin 47 is for pushing the roller from operative position and may be termed an unlocking pin, and the control lever 42 an unlocking lever. The parts are so timed that during the retraction of the needle through the work the roller is held in wedged position, so that the work rest resists the tendency of the needle to displace 85 the work. The work rest is never locked against forward movement and in each cycle 90 readjusts itself to any changes in position of the work.

The shank h of the back gage H is also arranged at the inner side of the frame wall 10. Its front end is confined by the same guide plate 39, already mentioned. The middle part of the shank h extends across an opening 53 in the wall so as to give access from the opposite side. Near its rear end the shank h is confined and guided by a plate or block 54. A spring 55 pulls constantly forward on the shank and back gage. 100

It is desirable to have a cushioned stop for the forward movement of the back gage when released. For this purpose its rear end is formed with a boss 56 through which passes a rod 57 screw threaded at its rear end where lock nuts 58 are adjustably secured. The boss 56 forms a stop for the forward movement of the lock nuts 58, a spring 59 pressing forward on the head 60 of the rod 57 to hold the parts yieldingly in the position illustrated. The rod head is arranged to abut against the fixed block 54 to limit the forward movement of the back gage. The spring device serves as a buffer to prevent shock and noise, and leather buffers 61 may be added at both contact points to give greater quietness. 110

When the machine is in the stopped position of Figs. 1, 2, 3 and 5, both the work rest and back gage are yieldable so that they will adapt themselves to the position of the 115 120 125 130

shoe as it is inserted. The workman fits the channel *w* to the channel guide *B* and during stitching this engagement gives the guidance of the shoe as it is fed progressively forward by the feed device *G*. The welt strip *w* is indicated in Figs. 1 and 6, as passing from the back gage member *H* to the point where the needle applies the stitches through the welt, the upper and the 10 insole lip. During the time when the work is stationary the back gage is caused to retract, so that when the work is subsequently fed forward a certain amount of welt will have been drawn from the supply, and will 15 be laid in place against the shoe by the member *H* preparatory to the advance of the needle for the succeeding stitch. The welt guide or back gage *H* comes forward into contact with the upper or last of the shoe, 20 limited by the stop devices 56-61. The subsequent retraction of the back gage does not take place until after the retraction of the needle because it operates, during the retraction of the needle, to firmly hold the work 25 forwardly. The retraction of the back gage when it occurs is of utility, not only for assisting the feed of the welt in making welt shoes, but for the purpose of removing this instrument from the shoe so that it will not 30 injure the shoe or impede its feed movement, which latter occurs while the shoe contacts and slides against the smooth surface of the work rest.

I will now describe a novel mechanism for 35 effecting the timed retraction of the back gage and its subsequent timed release, and it will be noted that after the back gage has come forward into contact with the shoe and become locked forward it is not at the same 40 time locked against forward movement, but is free so as to adapt itself at all times to the actual position of the shoe.

As a retracting means for the back gage I have shown a member 63 which, specifically, is in the form of a hook and is arranged to move forwardly and rearwardly by a regular amount and at a regular time, while the back gage is engaged with or released from the retractor at proper periods 50 of time.

The back gage retractor or hook 63 may be fitted to move rearwardly and forwardly in any suitable manner, for example, by being hung from a guiding arm 64 and the arm 55 29, already mentioned, which latter will be the actuating means through which the movements of the crank 12 are transmitted to the retractor. It will be understood that the hook 63 simply moves backwardly and forwardly in a regular timed manner, the back movement being timed so that the hook can pull rearwardly the back gage *H* at the proper point in the cycle. The engagement 60 between the back gage and the hook 63 may be effected by a complementary hook 65

mounted on the shank *h*. The hook 65 is pivoted at its front end so that it may be dropped into engagement with the other hook and lifted out of engagement, and its rear end is formed with an inclined surface 70 66 serving as a cam for the timed lifting of the hook to disengage the shank from the retractor. The drop of the hook 65 into the engaging position is limited by a stop device 75 67 and a spring 68 is arranged to assist the descent of the hook, tending to hold it in engagement with the retractor hook.

When the back gage, and its hook 65, are forward and the hooks disengaged, the subsequent engagement of the hooks is brought about by the forward travel of the lower hook or retractor 63, which rides under the inclined surface 66 and comes substantially to the position shown in Fig. 4. When the retractor hook draws rearwardly it engages 85 the other hook after a brief interval and then pulls it backwardly, retracting the back gage. The hooks are so relatively spaced as to engage at the proper point of time. The cessation of the rearward movement of the back 90 gage is effected by lifting the hook 65 out of engagement with the retractor. By setting this action to take place at a certain point of time the total retraction is controlled.

For unlatching or separating the hooks a pin 70 is shown, this standing in the path of the inclined surface 66, so that as the hook 65 is borne rearwardly it is cammed upwardly by the pin and so caused to disengage 95 from the other hook.

The unlatching pin 70 may be mounted on a carrier or lever 71 adjustable to regulate the timing of the disengagement. Fig. 1 shows that the forward arm of the lever 71 carries an adjusting screw 72 which contacts 105 with a fixed abutment 73. In this way the timing is adjusted at will. A spring 74 is shown for keeping the screw in contact with its abutment and maintaining the unlatching pin 70 in its operative position.

From the above it will be understood that in each cycle of stitching operation the hooks 64, 65 are engaged and the latter is pulled rearwardly so as to retract the back gage from the shoe, this movement being terminated by the disengagement of the hook, permitting the back gage to spring forwardly into contact with the shoe under the pull of the spring 55. This occurs while the needle moves forwardly. Before the needle is retracted it is necessary to lock forwardly the back gage so as to give added support to the work while the needle is drawing back. This may be done by the following clutching or locking device 77-79. A wedge roller or ball 77 is shown contacting the upper side of the shank *h* and at certain times contacting also the fixed wedge surface 78 formed at the left side of the block 54. A spring 115 actuated rod 79 presses the ball towards 120

locking position, as seen in Fig. 4. When in this position the back gage is free to move forwardly, but can not be moved rearwardly, and thus resists the pull caused by the retraction of the needle. It is necessary that the shank should be free from this locking action when the needle is not being retracted. For this purpose an unlocking rod 81 is arranged to press forwardly on the ball 77 so as to remove it from operative position, as in Figs. 3 and 5. The unlocking rod is actuated at certain times so as to cause the unlocking of the clutch 77-79 and permit its subsequent locking, in harmony with the stitching cycle. The rod carries a lateral pin 82 (Figs. 3 to 5) which is engaged by an unlocking lever operated under the control of a cam. The unlocking lever is fulcrumed at 83 and comprises the following parts all either integral or rigidly united.

The arm 84 is slotted at its upper end to receive the pin 82, and is pulled rearwardly by the spring 43. The arm is formed with a flat extension 85 arranged to cover and enclose the clutch elements. A rear extension 86 is connected by an adjusting screw 87 with an upward arm 88 having at its extremity a cam roll 89 contacting with a cam 90 associated and rocking with the three-armed lever 27-29. The cam 90 and the cam 44, previously mentioned, may be cooperatively formed and attached by bolt 91 to the sleeve of the three-armed lever, as seen in Fig. 1.

The cycle of operations may be briefly and partially described as follows. Figs. 1, 2, 3 and 5 show the parts in their position when the machine is stopped, the needle being fully retracted, the back gage being almost fully retracted by the hook 63 and both of the clutches 48-50 and 77-79 being open so that both the work rest and back gage are free to move rearwardly. As the operating shaft rotates from this position the needle starts forwardly toward the work. About this time the hook 65 is lifted free of the retractor hook and the back gage is snapped forwardly by its spring into contact with the shoe. The timing of this action is adjustable. By the time the needle has come to its full forward position, having penetrated the work, the take-up has also acted and the stitch is completed. This is the true end of the stitching cycle, but in practice the machine is not stopped at this point because of the difficulty in disengaging the work from the needle. While the needle is substantially at its forward position both of the clutches become locked by reason of the action of the cams 44 and 90 and from this time onward the work rest and back gage are locked against rearward movement, but not against forward movement. After the needle starts to retract the retractor hook comes to its full forward position, as seen in Fig. 4. It is about to move rearwardly and it will be

noticed that it has not yet contacted the hook 65. Therefore, the back gage is still not locked against forward movement. The retracting needle passes out of the work to its fully withdrawn position and thereupon both of the clutches are unlocked, their service having ceased. About the time the needle becomes fully retracted the hook 63, moving rearwardly, contacts the hook 65, thus commencing the retraction of the shank and the work gage. While this retraction is proceeding the parts come to the originally described position of Figs. 1, 2, 3 and 5, and if the machine is not stopped at this point the operations will be repeated as described. The timing of the feed movement of the work will be understood and is indicated in said prior patents. Substantially it occurs while the needle is retracted out of the work and before or simultaneous with the release of the back gage, so that the feed will be finished before the back gage snaps again into contact with the shoe. There is a certain latitude in timing of the various parts by the described adjustments and others.

It will thus be seen that I have described a sewing machine of the class mentioned, embodying the principles and attaining the objects and advantages of the present invention. Since many matters of combination, arrangement, design, construction, and detail, may be variously modified without departing from the novel principles involved, no limitation to such matters is intended except in so far as set forth in the appended claims.

What is claimed is:

1. In a welt-and-turn shoe-stitching machine, an operating shaft, a barbed needle reciprocated from said shaft, a crank 12 on said shaft, a pitman 21 on said crank, a guide arm 22 guiding said pitman and oscillated by it, a needle guide actuating lever 25 oscillated by said guide arm 22, in coordination with the needle, a looper D, and connections from the pitman 21 for actuating the looper in coordination with the needle.

2. In a welt-and-turn shoe-stitching machine, an operating shaft, a barbed needle reciprocated from said shaft, a back gage carried on its rearwardly extending reciprocating shank, resilient means pressing the shank forwardly, a lock operating intermittently to lock the shank in forward position while the needle is retracting from the work, and means regularly to retract the shank and back gage rearwardly and to release the same to return forwardly in each cycle, comprising a retractor, a cooperating contact on the back gage shank, connections for regularly reciprocating the retractor longitudinally of the shank, the retractor and contact arranged so that the retractor meets the contact always at the same point longitudinally in the length of the back gage shank and forces it rear-

wardly in each cycle, and timed means for effecting the disengagement of retractor and contact during the rearward movement of the retractor and after the needle has retracted out of the work to permit the back gage to return forwardly into contact with the work.

3. In a welt-and-turn shoe-stitching machine, an operating shaft, a barbed needle reciprocated from said shaft, a back gage carried on its rearwardly extending reciprocating shank, resilient means pressing the shank forwardly, a lock operating intermittently to lock the shank in forward position while the needle is retracting from the work, and means regularly to retract the shank and back gage rearwardly and to release the same to return forwardly in each cycle, comprising a retractor, a cooperating contact consisting of a swinging element pivoted on the back gage shank, connections for regularly reciprocating the retractor longitudinally of the shank, the retractor and contact arranged so that the retractor meets the contact and forces it and the shank rearwardly in each cycle, and timed means for effecting the disengagement of retractor and contact, namely, by swinging said pivoted element from the retractor, during the rearward movement of the retractor and after the needle has retracted out of the work, so as to permit the back gage to return forwardly into contact with the work.
4. A shoe stitching machine as in claim 3 and wherein the means for effecting disengagement by swinging the pivoted contact element from the retractor consists of a fixed member having cam cooperation with the swinging contact element such that the rearward movement of the parts causes the disengagement.

5. In a welt-and-turn shoe-stitching machine, an operating shaft, a barbed needle reciprocated from said shaft, a back gage carried on its rearwardly extending reciprocating shank, resilient means pressing the shank forwardly, a lock operating intermittently to lock the shank in forward position while the needle is retracting from the work, and means regularly to retract the shank and back gage rearwardly and to release the same to return forwardly in each cycle, comprising a retractor, a cooperating contact on the back gage shank, connections for regularly reciprocating the retractor longitudinally of the shank, the retractor and contact arranged so that the retractor meets the contact and forces it rearwardly in each cycle, and timed means for effecting the disengagement of retractor and contact during the rearward movement of the retractor and after the needle has retracted out of the work, said means comprising a device arranged to cause relative lateral separating motion between the retractor and contact, operated by reason of the rearward movement thereof.

6. A shoe stitching machine as in claim 3 and wherein the means for effecting disengagement by swinging the pivoted contact element from the retractor consists of a fixed member having cam cooperation with the swinging contact element such that the rearward movement of the parts causes the disengagement and the retractor is provided with means having similar cam cooperation with the swinging contact when coming forward for repeated operation.

In testimony whereof, I have affixed my signature hereto.

FRANK ZALESKI.
